Primary Examiner — J. Thorn, Sr.

(57) CLAIM

The ornamental design for a bra as shown and described.

DESCRIPTION

1.1: Perspective;

1.2: Front;

1.3: Back;

1.4: Right;

1.5: Left;

1.6: Top; and

1.7: Bottom

The design refers to a sports bra.

The broken lines in the drawings depict stitching that form no part of the claimed design.
